UNITED STATES PATENT OFFICE.

JOHN JOSEPH JOHNSTON, OF BENSON, MINNESOTA.

BEARING PLANE.

Application filed May 28, 1927. Serial No. 194,965.

The present invention relates to improvements in bearing planes and has for an object to provide an improved tool for truing faces or surfaces of gasoline motor connecting rods and main bearings, although the implement will be found of general utility in automobile and railroad shops and wherever a file surface is necessary.

An object of the invention is to provide a fixed file surface against which the part to be trued may be moved to avoid the difficult use of the present file which must be reciprocated against the fixed surface.

This difficulty in the use of the ordinary file is, even in a skilled mechanic's hands, the cause of ruin of a large number of mechanical parts and it is an object of the present invention to eliminate this difficulty and to provide a fixed and extensive file surface which will enable even the novice to perform a correct and accurate job.

With the foregoing and other objects in view, the invention will be more fully described hereinafter, and will be more particularly pointed out in the claims appended hereto.

In the drawings, wherein like symbols refer to like or corresponding parts throughout the several views,

30 Figure 1 is a perspective of an improved bearing plane constructed according to the present invention;

Figure 2 shows an elevation of a vise with the bearing plane, illustrated in section, 35 mounted therein;

Figure 3 is a bottom perspective of the improved bearing plane; and,

Figure 4 is a bottom perspective view of a slight modification.

40 Referring more particularly to Figures 1, 2 and 3, 5 represents a relatively thin, long and wide metallic plate on the upper working surface of which is wrought a milled file cutting face 6. On the reverse side of the plate 5, as shown in Figure 3, is a central longitudinal rib 7, substantially rectangular in cross section and transverse end ribs 8 and 9 with the central portions of which the longitudinal rib 7 merges. The transverse 45 ribs 8 and 9 are disposed flush with the ends of the plate 5.

As shown in Figure 4, the milled file plate 5^a is provided upon its reverse face with the reinforcing rib 7^a but the transverse ribs 55 are dispensed with, and companion longi-

tudinal side ribs 10 and 11 are provided being parallel with the central rib and spaced therefrom. These side ribs are substantially flush with the side edges of the plate 5^a.

In Figure 2 the bearing plate 5 is shown as clamped in the vise, the jaws of which are represented at 12 and 13. These jaws as shown are gripping upon opposite sides of the central rib 7. These sides of the rib are flat and parallel and the vise jaws also engage beneath the under surface of the plate 5 so that a right angular support is had by both jaws against the under sides of the plate 5 and the side faces of the rib 7.

The bearing plane may be clamped in 70 the vise or it may be placed upon a work bench. The bearing cap and bearing are held in the right hand while being pushed along the file cutting surface 6, the left hand being used to steady the work and keep 75

the same down with appropriate pressure against the milled cutting surface. The bearing or other work is pushed back and forth along this cutting surface 6 until the desired amount of abrasion is performed. 80

The requisite result will usually be had in three or four movements. The bearing cap is then reversed and the process repeated. It will be found comparatively easy to secure a true surface for the bearing cap and 85

also for the bearing. The tool is universal for all motor bearing. The milled file face will preferably be 14 in. long, 6 in. wide, and 1/4 in. thick. The plate 5 may be cut with the file surface and be made separately 90 from the ribs which may be of different material electrically welded or otherwise secured or by drop forging, or rolling same.

The rib 7 may advantageously be 1 in. in width 1/2 in. in depth. The transverse ribs 95 8 and 9 are also of the same width and depth as are the ribs shown in Figure 4. The rib 7 in Figure 3, will act not only as a support, as above stated, but will also reinforce the comparatively thin plate 5 and prevent its warping or buckling along transverse lines throughout its length. The transverse ribs 8 and 9 stiffen the ends of the plate 5 and they intersect at right-angles and join with the longitudinal rib 7 thus providing a 100 strong structure and one that will prevent the warping or buckling of the bearing plate 5 also along longitudinal lines.

The side longitudinal ribs 10 and 11 in Figure 4 stiffen the plate 5^a along its side 110

edges and the presence of the three longitudinal reinforcing ribs which extend all the way to the ends of the plate 5^a sufficiently stiffen the plate against both longitudinal and transverse stresses.

It will be obvious that many changes in the construction, combination and arrangement of parts could be made, which could be used without departing from the spirit of my invention, and I do not mean to limit the invention to such details, except as particularly pointed out in the claim.

Having thus described my invention, what

I claim and desire to secure by Letters Patent of the United States is:—

A bearing plane comprising a thin, wide and long plate having a working file surface, a longitudinal central rib secured to the reverse surface of the plate, and transverse ribs secured also to the reverse surface of the plate merging centrally and at substantial right angles at the ends of the longitudinal rib, said transverse ribs being substantially flush with the ends of said plate.

JOHN JOSEPH JOHNSTON.
